UNITED STATES PATENT OFFICE.

ROBERT CARL RAHM, OF WYOMISSING, PENNSYLVANIA.

DYEING MACHINE.

Application filed July 19, 1922. Serial No. 575,941.

To all whom it may concern:

Be it known that I, ROBERT CARL RAHM, a citizen of the United States, residing at Wyomissing, in the county of Berks and 5 State of Pennsylvania, have invented certain new and useful Improvements in Dyeing Machines, of which the following is a specification.

My invention relates particularly to dyeing machines which employ a fabric receptacle pivotally movable into and out of the liquid tank in connection with an agitator pivotally movable into and out of said receptacle; and my main object is to provide 10 improved operating means for these movable parts whereby both required rotation of the agitator, and intermittent raising and lowering thereof and of the heavily loaded or empty receptacle, may be most conveniently 15 and satisfactorily effected. The invention is fully set forth in connection with the accompanying drawing and the novel features are clearly defined in the subjoined claims.

Fig. 1 is a diagrammatic front elevation of 20 a complete machine embodying my invention in preferred form; partially raised positions of the swinging parts being indicated in dotted lines.

Fig. 2 is mainly an end elevation of the 25 same, but with certain of the parts shown in cross-section on the lines 2—2, 2^a—2^a of Fig. 1; the agitator arms and engaging wheels being represented as swung to the dotted-line position of Fig. 1.

Fig. 3 is a sectional plan view of the main 30 drive shaft and its clutch-connected countershaft.

The fabric receptacle 5 is pivotally connected at 6 to the frame 7 in which the liquid 35 tank 8 is fixed, so as to swing into and out of the latter in an arc 5^a as indicated; and the agitator 10 rotatable with shaft 11, is carried by arms 12 arranged to swing in the arc 10^a upon the transverse axle 13 so as to 40 lower or raise the agitator into or out of the receptacle 5; this general arrangement being known as set forth in Smith's Patent No. 794,560 of July 11, 1905.

Quadrant arms 15, 15 fixed to the pivot 45 shaft 6 with the fabric receptacle 5, mesh with gear wheels 16, 16 so that rotation of the latter will raise or lower said receptacle; said gear wheels 16 rotating upon an axis 13^a eccentric to said pivotal axle 13, and said 50 agitator carrier arms 12 being also raised or

lowered thereby upon the pivotal axle 13 as hereinafter further described; while rotary movement is imparted to the agitator itself through a double sprocket sleeve 20—21, (Fig. 2) which is loosely mounted on an end 60 of said pivotal axle 13 and carries a drive chain 22 engaging with a sprocket wheel 23 fixed to the agitator shaft 11, (Fig. 1).

Desired turning of the gear wheels 16 to cause raising or lowering of the receptacle 5 and agitator 10; and of the double sprocket-wheel sleeve 20—21 to rotate the agitator; is effected by a common power shaft 25; this being effected through an intermediate drive shaft 26, which is provided with fixed 65 pinions 27 arranged in mesh with said gear wheels 16, and also with a loosely mounted sprocket wheel 28, 28^a directly driven by said power shaft and carrying a chain 29 arranged to drive said sprocket-wheel sleeve 70 20—21.

This intermediate shaft 26 must be rotated in reverse directions so as to either raise or lower the receptacle and agitator, as desired; and to accomplish this I employ in connection 80 with the power shaft 25, a countershaft 36 adapted to be driven in reverse directions as determined by operation of a clutch sleeve 40 thereon. The power shaft 25, as shown

particularly in Fig. 3, is driven by a motor 35, and is arranged to directly drive the agitator-rotating sprocket wheel 28 on shaft 26, by means of a worm wheel 28^a fixed to 85 said sprocket wheel and arranged in engagement with a worm 41 fixed to said power shaft. The countershaft 36 loosely carries two spaced-apart pinions 42 and 43 respectively; pinion 42 being arranged in direct 90 mesh with a fixed gear 44 on said power shaft, and pinion 43 being in indirect mesh

through an idler 45 (Fig. 1), with a similar fixed gear 46 thereon; while the intermediate splined clutch sleeve 40 is movable from the 95 normal neutral position indicated, into engagement with either pinion 42 or 43 so as to cause rotation of the countershaft respectively in reverse or like direction to the power shaft. The countershaft is also provided with fixed worm 41^a, which is arranged in engagement with a worm wheel 47 fixed to the drive shaft 26. Thus when 100 the power shaft 25 only is driven, as indicated, the only effect is to rotate the agitator; while when the clutch is moved to engage the countershaft therewith both the 105

agitator carrier arms 12 being also raised or 110

agitator and fabric receptacle will be simultaneously swung, upward or downward as desired.

As previously stated, rotation of the gear wheels 16 not only raises or lowers the fabric receptacle 5, but also simultaneously raises or lowers the agitator 10; the latter movement being effected independently of the rotation of the agitator by the operating 10 chains 29 and 22 upon the loosely mounted double sprocket sleeve 20—21 on axle 13. To provide for starting and stopping the swinging movement of the agitator in proper relation to the corresponding movement of 15 the fabric receptacle, I provide for automatically engaging the wheel or wheels 16 with the agitator carrying arms 12; this being effected, as shown, by the mounting of said wheels upon the stud axis 13^a eccentric to the pivotal axle 13 of said carrying arms 20 as previously mentioned, and by providing the inner face of one or both wheels 16 with a projection 50 having spaced flanges 51 and 52 of different radial extent and adapted to engage and disengage a lateral projection 53 on the carrying arm 12. As shown in Fig. 1 the projection 53 is in full engagement between the flanges 51 and 52 of the wheel projection; but as the wheel rotates on its eccentric stud axis 13^a while the carrier arms 12 swing upon the pivotal axle 13, the arm 12 is disengaged from the wheel 16 when the agitator has been sufficiently swung (as is indicated in the dotted lines) so as to allow 30 the wheel 16 to continue the elevating of the fabric receptacle while the agitator remains in suitably supported elevation. In lowering the parts the agitator arms are similarly engaged automatically as required.

35 The movement of the clutch 40 is effected by a pivoted clutch arm 55, which may be operated by a suitable hand lever 56 to start raising or lowering of the receptacle and agitator; but provision is made for automatically returning the clutch to disengaged neutral position upon completion of the desired raising or lowering movement, by providing the wheel 16 with stop projections 57, 57^a adapted to oppositely engage the clutch 40 arm 55 at determined points of the wheel rotation.

It will be understood that usual means may be readily provided for counterbalancing the weights of both the receptacle 5 and agitator, as is indicated at 12^a, 12^b in connection with the latter; and that the detailed construction set forth may be readily modified. My invention enables the raising of the parts for emptying and filling, and the 60 relowering of same for treatment of the fabrics, to be effected with such facility and simplicity of mechanism and operation as is of great practical advantage.

What I claim is:

65 1. The combination with a liquid tank, a

pivoted fabric receptacle mounted to swing into or out of said tank, and a rotary agitator pivotally mounted to swing into and out of said receptacle; of a common drive shaft and intermediate operating means 70 adapted to either rotate said agitator independently, or to swing both said agitator and receptacle.

2. The combination with a liquid tank, a pivoted fabric receptacle mounted to swing 75 into or out of said tank, and a rotary agitator pivotally mounted to swing into and out of said receptacle; of a common drive shaft and intermediate operating means adapted to rotate said agitator and simultaneously 80 swing both the agitator and said receptacle.

3. The combination with a liquid tank, a pivoted fabric receptacle mounted to swing 85 into or out of said tank, and a rotary agitator pivotally mounted to swing into and out of said receptacle; of a common drive shaft and intermediate operating means adapted both to rotate said agitator and to selectively raise or lower the agitator and said receptacle jointly.

90 4. The combination with a liquid tank, a pivoted fabric receptacle mounted to swing into or out of said tank, and a rotary agitator pivotally mounted to swing into and out of said receptacle; of means for jointly raising or lowering said agitator and receptacle, and means for determinedly stopping the movement of one of said parts while continuing the other.

95 5. The combination with a liquid tank, a pivoted fabric receptacle mounted to swing 100 into or out of said tank, and a rotary agitator pivotally mounted to swing into and out of said receptacle; of means for jointly raising or lowering said agitator and receptacle, means for automatically stopping the movement of one of said parts while 105 continuing the other.

110 6. The combination with a liquid tank, a pivoted fabric receptacle mounted to swing into or out of said tank, and a rotary agitator pivotally mounted to swing 115 into and out of said receptacle; of a main drive shaft, a countershaft having a reversing clutch-gear connection thereto, rotating means for said agitator operated by said main shaft, and swinging mechanism for said receptacle and agitator jointly operated by said countershaft.

120 7. The combination with a liquid tank, a pivoted fabric receptacle mounted to swing into or out of said tank, and a rotary agitator pivotally mounted to swing into and out of said receptacle; of a main drive shaft, a countershaft having a reversing 125 clutch-gear connection thereto, rotating means for said agitator operated by said main shaft, swinging mechanism for said receptacle and agitator jointly operated by said countershaft, and clutch-operating 130

means adapted to automatically stop the swinging action in each direction.

8. The combination with a liquid tank, a pivoted fabric receptacle mounted to swing into or out of said tank, and a rotary agitator pivotally mounted to swing into and out of said receptacle; of a main drive shaft, a countershaft having a reversing clutch-gear connection thereto, rotating means for said agitator operated by said main shaft, swinging mechanism for said receptacle and agitator jointly operated by said countershaft, means for automatically connecting and disconnecting the agitator and receptacle for determined swinging periods, and clutch-operating means for automatically stopping the swinging action in each direction.

9. The combination with a liquid tank, a pivoted fabric receptacle mounted to swing into or out of said tank, and a rotary agitator pivotally mounted to swing into and out of said receptacle; of a main drive shaft, a countershaft having a reversing clutch-gear connection thereto, an intermediate shaft in gear with said countershaft and loosely carrying an agitator drive wheel arranged in gear with said main shaft, a receptacle-swinging gear wheel driven by said

intermediate shaft and arranged to also 30 swingingly engage said agitator, and a loosely-mounted sprocket wheel arranged to transmit rotary motion from said drive wheel to the agitator.

10. The combination with a liquid tank, a pivoted fabric receptacle mounted to swing into or out of said tank, and a rotary agitator pivotally mounted to swing into and out of said receptacle; of a main drive shaft, a countershaft having a reversing clutch-gear connection thereto, an intermediate 40 shaft in gear with said countershaft and loosely carrying an agitator drive wheel arranged in gear with said main shaft, a receptacle-swinging gear wheel driven by said 45 intermediate shaft and arranged to also swingingly engage said agitator, and a loosely-mounted sprocket wheel arranged to transmit rotary motion from said drive wheel to the agitator; said receptacle-swinging 50 gear being mounted eccentrically to the pivot axes of the agitator carrier arm and adapted to periodically engage and disengage the latter.

In testimony whereof I affix my signature.

ROB. CARL RAHM.
